WATER-VALVE FOR INSTANTANEOUS WATER-HEATERS

1,247,157.

Specification of Letters Patent. Patented Nov. 20, 1917.

Application filed June 15, 1915. Serial No. 34,250.

To all whom it may concern:

Be it known that we, EDWIN RUUD, a citizen of the United States, and resident of Pittsburgh, in the county of Allegheny and

5 State of Pennsylvania, and HERBERT S. HUMPHREY, a citizen of the United States, and resident of Kalamazoo, in the county of Kalamazoo and State of Michigan, have invented certain new and useful Improvements in Water-Valves for Instantaneous Water-Heaters, of which the following is a specification.

This invention has particular reference to the water valve which serves to actuate the 15 gas valve, opening the latter for the passage of gas to the burners when water is being delivered from the heater, and the primary object is to provide simple and efficient means for passing water to the heater 20 through the water valve without interfering with the gas-valve operating function of the latter.

Under certain conditions it is desirable to embody the water valve in a packed piston, 25 and in order to preserve the packing the arrangement should be such as to avoid movement of the packing over ports or offsets in the casing in which it travels, and to accomplish this the piston itself must be 30 ported for the passage of water therethrough instead of therearound. The present invention is immediately concerned with a valve control of efficient and novel form for the piston port.

35 The invention may be variously embodied, some desirable adaptations thereof being illustrated in the accompanying drawings, wherein Figure 1 is a vertical sectional view of a water valve showing one form of the 40 invention, the same being illustrated in connection with a conventional embodiment of a gas valve, and Fig. 2 is a sectional view of a water valve of modified construction.

Referring to the drawings, 1 designates 45 a water valve casing having the cylindrical intermediate portion 2. One end of the casing is provided with a water inlet 3, and its opposite end with an outlet 4. As here shown, the inlet end is closed by the removable head or cap 5 for gaining access to the valve mechanism. Fitting and movable within part 2 of the casing is piston 6 which is preferably provided with packing 7, the

arrangement being such that the piston completes its movement in opposite directions 55 without causing the packing to traverse either the inlet or the outlet ports.

Adapted to be actuated by piston 6 is stem 8 which aligns with stem 9 of gas valve 10, the latter being conventionally shown 60 as normally closing port 11 of gas chamber 12 under the influence of spring 13. The water and gas valve structures may be held in operative relation by any desired 65 form of frame element or support such as bracket 14. The co-operation of stems 8 and 9 and the slight independent movement of stem 8 afforded by gap 15 are well understood in the art, and need not be described in detail.

In the embodiment illustrated in Fig. 1, piston 6 is centrally ported at 16, and the port is normally closed by the upwardly opening check valve 17 with fingers 18 projecting therefrom through port 16 and adapted to engage the stop-forming boss 19 in the outlet portion of the casing. Stem 8 extends through port 16, and is secured by spider 20 to the inlet side of the piston. Check valve 17 is movable on stem 8, is 80 adapted to open toward the casing inlet, and is normally closed by spring 21. Piston 6 is held normally projected toward the inlet end of the casing by spring 22.

In operation, upon lowering the pressure 85 in outlet 4, as by opening a faucet served by the heater, the main pressure at inlet 3 advances the piston in opposition to spring 22 thereby opening the gas valve through the coaction of stems 8 and 9, as will be 90 understood. The arrangement is preferably such that the piston travels through a considerable portion of its gas-valve opening movement and opens said valve before check valve 17 is opened by stop 19. When this 95 stop is reached it stops the forward movement of check valve 17 and is thus caused to open toward the casing inlet in opposition to spring 21, thereby opening port 16 and permitting water to pass through the piston 100 from the casing inlet 3 to outlet 4. Upon closing the faucet, the pressures at opposite sides of the piston are equalized through the small port 23 and the piston is restored to normal position by spring 22, and valve 105 17 is permitted to close under the pressure

of spring 24. The back and forth movement of piston 6 in either direction does not carry packing 7 over either the casing inlet or outlet so that the piston is maintained 5 water-tight.

In Fig. 2, valve 17 is provided with the solid shank 24 which engages the upper extremity of rod 8 instead of passing the latter upwardly through the valve and securing 10 it to the upper portion of the piston as in Fig. 1; otherwise the construction is the same. As rod 8 is not positively connected to the piston but receives its gas-valve opening force through check valve 17, the check 15 valve spring 21 must be stronger than gas-valve spring 13 so that the check valve will remain closed until the gas valve has been opened.

It is characteristic of each adaptation 20 that the piston controlling valve opens toward the casing inlet and hence its tendency is to close under the main pressure in the casing inlet. The valve travels with the piston during the first portion of the forward movement and until the gas valve has been opened. Movement of the piston check 25 valve is then arrested, thereby opening the piston port for the passage of water from the casing inlet to its outlet. And in each 30 construction the travel of the packed portion of the piston is through a smooth or unported portion of the casing so that there is no tendency to cut or unduly wear the packing. It is further characteristic that 35 the water valve piston is ported centrally, thereby causing the pressure to be equal at all points around the ported center and avoiding cramping and sticking of the piston within the casing.

40 We claim:

1. In a water valve for instantaneous water heaters, the combination of a casing having a water inlet and an outlet, a piston movable in the casing between the inlet and outlet, the piston formed with a central chamber open at its ends for the passage of water, a check valve movable within the chamber for closing one end thereof, a spring 45 confined within the chamber for opposing opening movement of the check valve, means made operative by the movement of the piston for opening the check valve, a normally

closed gas valve, and means actuated by the piston for opening the gas valve.

2. In a water valve for instantaneous 55 water heaters, the combination of a casing having a water inlet and an outlet, a ported piston movable in the casing between the inlet and outlet, a gas-valve actuating stem secured to the piston and extending through 60 the piston port and also through the said casing, a check valve for the piston port slidable on said stem, and means made operative by movement of the piston for opening said check valve.

3. In a water valve for instantaneous water heaters, the combination of a casing having a water inlet and an outlet, a ported piston movable in the casing between the inlet and outlet, a gas-valve actuating stem 70 secured to the piston and extending through the piston port and through the casing, a check valve for the piston port, the valve formed with an opening through which said rod extends and by means of which the check 75 valve is guided in its opening and closing movements, and means made operative by movement of the piston for moving the check valve on the rod and thereby opening the same.

4. In a water valve for instantaneous water heaters, the combination of a casing having a water inlet and an outlet, a piston movable in the casing between the inlet and outlet, the piston ported for establishing 85 communication between the inlet and outlet, a gas-valve actuating rod secured to the piston and movable therewith and extending therefrom through the outlet portion of the casing, a check valve for the piston 90 port movable with the piston and adapted to open toward the casing inlet, the valve formed with an opening for sliding on the rod when opening and when closing, and means made operative by the movement of 95 the piston toward the casing outlet for opening said check valve.

In testimony whereof we affix our signatures in presence of two witnesses.

EDWIN RUUD.
